Lubbock County, Tex. 79405

Filed May 5, 1969, Ser. No. 17,004

Term of patent 14 years

Int. Cl. D15—06

U.S. Cl. D49—1

FIG. 1

FIG. 2

FIG. 3

FIG. 4

FIG. 1 is a front and end perspective view of a laundry washer unit showing my new design, showing only a part of a row of machines for better clarity;

FIG. 2 is a top plan view thereof showing a complete row of machines;

FIG. 3 is a partial front elevational view thereof, the remainder of the row of machines as seen in FIG. 2 would be a repetition of those seen in FIG. 3, and the back elevational view would be identical; and

FIG. 4 is an end view thereof, the opposite end being identical in appearance.

I claim:

The ornamental design for a laundry washer unit, as shown and described.
